UNITED STATES PATENT OFFICE.

EZRA W. VANDUZEN, OF NEWPORT, KENTUCKY.

GRATE-BAR.

SPECIFICATION forming part of Letters Patent No. 360,067, dated March 29, 1887.

Application filed July 17, 1886. Serial No. 208,227. (No model.)

To all whom it may concern:

Be it known that I, EZRA W. VANDUZEN, a citizen of the United States, and a resident of the city of Newport, in the county of Campbell and State of Kentucky, have invented certain new and useful Improvements in Grate-Bars, of which the following is a specification.

The upper part of a grate-bar is heated to a much higher degree than the lower part, because of its more immediate contact with the fire. In consequence of this unequal heating the upper part expands more than the lower part of the bar. This difference in longitudinal expansion between the top and the bottom of the bar causes it to bow upwardly. This shape is not altogether lost when the bar is cooled, and after continued use the bar finally assumes a permanently-curved shape, in which the longer or convex side is uppermost. Besides interfering with the fire, a bar so distorted burns out very quickly. In addition to the distortion in the vertical plane, the bar also expands laterally, and when one side expands more than the other the bar becomes permanently curved laterally, in the same manner as the permanent bowing in the vertical direction was produced. This lateral distortion produces a wide space between the bars, allowing the fuel to drop through, and also allowing the hot coal to come in contact with the sides of the bars, burning them out and aiding in warping them laterally.

To avoid these defects in the construction of the bar and disadvantages arising therefrom is the object of my invention.

In the accompanying drawings, forming part of this specification, Figure 1 is a perspective view of my improved grate-bar. Fig. 2 is a vertical cross-section taken at the line $x-x$, Fig. 1. Fig. 3 is an enlarged view illustrating the manner in which the vertical slots in the bar are gradually closed by continuous use. Fig. 4 is a top view of a grate made with my bars, and illustrating two methods of arranging the bars. Fig. 5 is a side elevation of a smelting-furnace grate-bar constructed according to my invention.

The bar A is made of suitable depth throughout to support the weight put upon it. The sides taper slightly from above downward, as shown in Fig. 2. Each end of the bar is formed in the customary manner, the bar for smelt-

ing furnaces being provided at one end with the extension or handle B and at the other end with the end portion B', the bar for boiler and heating furnaces being provided at each end with the end portion B'. These end portions B' are also preferably provided with the side projections, e, separating the bars from one another. Ridges C C, placed at suitable intervals along each side of the bar, also assist in keeping the grate-bars at a proper distance from each other. The extension-pieces B and the ends B' in one case and the ends B' in another case rest on supports in the grate.

The upper edge of the bar is provided with a number of transverse slots, D. It is essential to the successful working of the bar that these slots conform to certain rules: first, the slots should not be placed close together, the length of metal between adjacent slots being preferably from three to four times the width of a slot; second, the slots should be cut rather deep into the bar, so that they may extend entirely through that part of the bar which is subjected to the greatest heat; third, it is preferable to make the slots tapering, as shown in the drawings; but this point is not essential to a successful operation of the bar.

When the bar is in use, its upper part expands in the way already described for grate-bars in general; but in this case the bar is not distorted, because the excess of longitudinal expansion of the upper part of the bar is accommodated by the slots D. I have discovered that the permanent expansion of the bar is confined to its upper one-third to one-half, and the slots D, extending preferably through about two-fifths of the whole depth of the bar, entirely compensate for the change in shape. When the slots are placed too close together, the intervening metal parts become mere stilts projecting upward from the bar proper, and burn rapidly away, and soon let the fire down upon the lower portion of the bar, and consequently fail to protect that part of the bar from distortion. When the slots are not sufficiently deep, they likewise fail to prevent distortion, because the metal immediately below them belonging to the part of the bar which should not be subject to permanent expansion being heated to a high degree produces a degree of distortion, in the manner already described.

In my bar the expansion of the upper part of the bar is confined to and divided between the sections E, which are between the slots D. Each section E as it expands extends each end 5 of its own section longitudinally, but does not buckle upward. The permanent expansion of the sections E gradually fills up the slots D, as shown in Fig. 3, where the dotted lines indicate the outline of the slot after permanent ex- 10 pansion has occurred. The bars are sometimes made so that in arranging the grate the slots D are opposite each other, as shown in Fig. 4, and again the bars are made so that when placed in position each slot D is opposite one 15 of the sections E, also shown in Fig. 4.

The advantages of a grate-bar possessing the properties of my bar as above set forth are quite obvious. Such a bar costs less than a bar not provided with slots, and its durability 20 is much greater. My grate-bar also admits

more air to the fire and supports the fuel on a less surface, and there is less obstruction to the air which supplies the fire with oxygen in reaching the burning fuel than in the ordinary grates.

25

A grate provided with a set of my bars will always have a flat surface, much facilitating firing, and securing greater uniformity in the fire itself.

What I claim as new and of my invention, 30 and desire to secure by Letters Patent, is—

A grate-bar provided with the tapering slots D, extending entirely through the permanently-expansible portion of the bar, as and for the purposes set forth.

EZRA W. VANDUZEN.
